BUILDING MATERIAL

Application filed December 2, 1930. Serial No. 499,478.

This invention relates to a construction of composition building material and has especial reference to material of this nature adapted for covering side walls of buildings. It has been known to use so-called strip shingles, for covering side walls of buildings, composed of a felted fabric, saturated with a waterproofing material such as bitumen or asphalt and coated on one or both sides with a layer of blown asphalt, in which is partially embedded a surfacing layer of comminuted granular material, such as crushed slate or the like.

The square butt shingle that may be used for this purpose comprises a body that has at one end thereof a series of projections or tabs spaced from each other by means of slots or recesses. The surfacing material is applied in such a way that when these strips are laid in successive overlapping courses, they will simulate a brick wall having broken mortar joints. The mortar joint simulation has a width substantially equal to that of a slot in the strips and completely surrounds each brick simulating area and in order that the finished surface shall closely simulate the appearance of a brick wall, it is essential that the mortar joint simulations between the successive courses be of uniform width throughout the length of the wall of the structure.

Thus it is evident that each strip must be placed at a certain, fixed position in order to properly locate the strips so that the desired effect is secured.

In the practical application of these strips, considerable difficulty is encountered in properly aligning the successive courses to secure the desired brick-simulating effect. This is due to the flexible and pliable nature of the material which makes it exceedingly difficult for the workman to hold the strip in proper position during the nailing operation to ensure that after the nails are driven home, the lower edge of the strips will be in the position, in relation to the preceding course, necessary to simulate accurately a horizontal, uniform and unbroken mortar joint between the courses. This difficulty is aggravated by the fact that these strips are generally made in lengths from thirty to forty or more inches

and it is very troublesome for the workman to hold these strips in proper position on a vertical surface during the nailing operation.

The object of the present invention is to provide a shingle strip construction adapted to overcome the above objections and this, broadly stated, is accomplished by employing indicating means on the strips, to facilitate handling thereof in applying them to a vertical wall without undue loss of time by the workman.

When shingle strips embodying my invention are used to secure a covering to the side walls of a building, the first course is laid in the usual manner. Subsequently the applicator pivots a strip, that is to form a portion of the next succeeding course, at a position where the indicating means of the strip of the first course is in registry with that of the strip of the second course. The strip of the second course is now swung about the pivot until it is in the desired horizontal position and is then fastened at any convenient points.

Thus, these marked shingle strips together with the novel method of application afford a very simple, expeditious, inexpensive and fool-proof method of laying shingle strips whereby the configuration of the covering is predetermined and exact.

With the aforementioned objects in view, this invention consists generally of a shingle strip marked or formed with indicia for the purpose described and a novel method of laying the same as will be fully described and illustrated in the following specification and in the drawing, in which:

Figure 1 represents a plan view of the shingle strip embodying my invention;

Figure 2 represents a section of the finished covering;

Figure 3 is a vertical cross-sectional view of Figure 2 and

Figure 4 illustrates in plan view one method of applying the shingle strips to the wall.

As shown the strip comprises a head or upper portion 11 and a lower or exposed portion 12 having a series of spaced slots 13 extending transversely thereof, to provide projections or tabs, with the upper edges 14

of the slots defining the exposed limit of the strips.

It will be understood that these strips will preferably be formed from a sheet of felt, 5 saturated with a waterproofing compound and coated on one or both faces with a layer of waterproofing material, such as high melting point blown asphalt. The upper or exposed face of the strips has suitable surface 10 facing material partially embedded in the coating layer on this face and in accordance with the preferred embodiment of this invention, coarse slate or slag of red or other brick color is applied to the tabs and covers the 15 same to a distance slightly below the upper edges 14 of the slots. The remaining area of the strip is surfaced with a black colored grit preferably of much finer mesh than the brick colored surfacing grit on the tabs. By 20 referring to Figure 1, it will be clear that the surfacing material is thus divided into two zones of distinctly contrasting colors, with a line of demarcation 15 between the two zones which lies a slight distance below 25 the upper ends of the slots. When these strips are employed as brick simulating siding, it is essential that the line of demarcation between the brick colored areas on the tabs and the dark colored area on the remainder 30 of the strip shall extend precisely parallel to the butt edge of the strip, so that when the strips are laid in overlapping courses, with their butt edges in registry with the tops of the slots in the strip of the next preceding 35 course, the dark colored mineral surfacing of said strips on the next preceding course will present the appearance of a horizontal mortar line along the lower borders of the brick simulating tabs.

40 In order that these strips may be rapidly applied and nailed in place with the assurance that the horizontal mortar simulating lines between successive courses shall be of uniform and unvarying width, the head of 45 each strip is formed with a plurality of markings or indicia shown at 16 and 17 with the markings or indicia 16 located at predetermined positions in the upper portion of strip that is lapped by the next succeeding 50 course. The markings or indicia 17 are also arranged on that portion of the strip that is lapped by the next succeeding course and are located in predetermined positions thereon, 55 such that when one strip is laid on the other, the markings 17 of the upper strip will be in registry with the markings 16 of the preceding strip. These markings or indicia may be in the form of a depression, projection, hole or the like and further are preferably located near each end of the strips so 60 that the applicator may lay the strips from left to right or vice versa.

The novel method of laying the strips embodying my invention consists in laying the

first course in the usual manner, subsequently pivoting a strip of the next succeeding course, which may be held so that its major axis extends in a vertical direction, by driving a pivot means, such as a nail 18, through one of the markings or indicia 17 and the corresponding indicia or marking 16 on the preceding course, with care being taken not to drive the pivot home, but a sufficient distance so that the pivot will hold the strip. The strip is then swung about said nail 18 as a pivot until the other marking 17 of the upper strip is in registry with the other marking 16 of the preceding or lower strip, or until the lower ends of the tabs are in registry with the upper edges of the slots. After the horizontal position of the strip is attained by following either of the methods above set forth the strip is nailed at any convenient points in the customary manner. This process is continued until the covering is complete.

It is to be understood, however, that the position of the marking or indicating means although predetermined may vary on the strips depending on the various designs to be attained and the particular type of strips used. The square butt strips hereinbefore referred to and described in detail, and the particular method of laying these strips so that a brick, mortar joint simulating covering may be produced is given by way of illustration and is not by any means to be construed by way of limitation.

I claim as my invention:

1. A shingle strip adapted to be laid in successive overlapping courses with its major axis horizontal, said strip having indicating means thereon, said means being located at such predetermined positions on the strip that when a nail is driven therethrough while the major axis of the strip is in a vertical direction, and the strip is swung about the nail as an axis to a position with its major axis extending in a horizontal direction, the lower edge of said strip will be spaced a predetermined distance from the lower edge of the next preceding course.

2. A shingle strip having indicating means thereon, comprising a plurality of perforations in the upper end of the strip, one of said perforations being adapted to register with another of said perforations in a superposed strip when the strips are laid in overlapping courses, said perforations being located at such positions that a nail may be driven through the registering perforations while the major axis of the strip extends in a vertical direction and the strip swung about the nail as an axis to its final position.

3. A shingle strip adapted to be laid with its major axis horizontal having thereon two distinct adjoining differently colored zones extending in the direction of the major axis with a clear line of demarcation where said

zones are contiguous, means on said strip so located as to determine the horizontal and vertical position of the strip when its major axis extends in a vertical direction and to afford a center when a nail is driven therethrough, so that when the strip is swung to a position with its major axis in a horizontal direction the lower edge of the strip will be located at a predetermined distance from the line of demarcation on the next preceding strip.

4. A shingle strip adapted to be laid with its major axis horizontal having two distinct adjoining zones of differently colored surface material thereon extending in the direction of the major axis, with a clear line of demarcation where said zones are contiguous, pivot indicating means being so located thereon as to determine the vertical and horizontal position of said strip when its major axis extends in a vertical direction and to afford a center about which the strip may be swung to a position whereby the lower edge of the strip is located at a predetermined distance from the line of demarcation on the next preceding course.

5. A shingle strip having a plurality of indicating means in the upper end of the strip adapted to register with indicating means in a subjacent strip when the strips are laid in overlapping courses, said first mentioned indicating means being located at such positions that a nail may be driven through one of said means while the major axis of the strip extends in a vertical direction and the strip may be swung about the nail as an axis to its final position.

6. A shingle strip having a plurality of indicating means in the upper end thereof, at least one of said means being adapted to register with a similar means in a superposed strip when the strips are laid in overlapping courses said means being located at such positions that a nail may be driven through the registering means while the major axis of the strip extends in a vertical direction and the strips may be swung about the nail as an axis to its final position.

Signed at Boston, in the county of Middlesex and State of Massachusetts this 28th day of November A. D. 1930.

RALPH W. B. READE.
